US0D1069745S

(12) **United States Design Patent** (10) Patent No.: **US D1,069,745 S**
 Kang (45) Date of Patent: ** Apr. 8, 2025

(54) **COMBINED WIRELESS CHARGER AND SPEAKER**

(71) Applicant: **Pingping Kang**, Jiangxi (CN)

(72) Inventor: **Pingping Kang**, Jiangxi (CN)

(**) Term: **15 Years**

(21) Appl. No.: **29/896,442**

(22) Filed: **Jul. 4, 2023**

(51) LOC (15) Cl. **14-01**

(52) U.S. Cl.

USPC **D14/172**

(58) **Field of Classification Search**

(57) **CLAIM**

The ornamental design for a combined wireless charger and speaker as shown and described.

DESCRIPTION

FIG. 1 is a perspective view of a combined wireless charger and speaker showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a rear, right, bottom perspective view thereof.

The broken lines in the drawings depict portions of the combined wireless charger and speaker that form no part of the claimed design.

1 Claim, 8 Drawing Sheets
